J. GEMZA

ANTISLIPPING DEVICE

Filed Nov. 19. 1924

Inventor
John Gemza

UNITED STATES PATENT OFFICE.

JOHN GEMZA, OF DANBURY, CONNECTICUT.

ANTISLIPPING DEVICE.

Application filed November 19, 1924. Serial No. 750,761.

To all whom it may concern:

Be it known that I, JOHN GEMZA, a citizen of Poland, and resident of Miry Broock, Danbury, in the county of Fairfield and 5 State of Connecticut, have invented certain new and useful Antislipping Devices, of which the following is a specification.

This invention relates to improvements in antislipping devices, particularly ice-creepers, designed for attachment to the heels of 10 boots or shoes, and has for its principal object to provide a novel device which can be readily attached to and detached from the heel of a boot or shoe.

15 Another object of the invention is the provision of a creeper of this character which can quickly be adjusted to any size of heel and locked in its adjusted positions.

A further object of the invention is the 20 provision of a creeper for the heels of footwear of simple and inexpensive construction provided with means for securely engaging the material of the shoe at the heel thereof in front as well as in rear thereof.

25 These and other objects and advantages of my invention will become more fully known as the description thereof proceeds, and will then be specifically pointed out in the appended claims.

30 In the accompanying drawing, forming a material part of this disclosure:

Figure 1 is a side view of a creeper constructed according to the invention, attached to a heel.

35 Figure 2 is a bottom plan view of the same looking in the direction of the arrows 2—2 of Figure 1.

Figure 3 is a similar view to Figure 1 with the creeper in position ready for attachment 40 to a heel.

Figure 4 is a cross-section on line 4—4 of Figure 1.

Figure 5 is an end view looking in the direction of arrows 5—5 of Figure 1.

45 The creeper comprises a top or heel engaging plate 10 having at one end upstanding heel engaging fingers 11 or the like, equipped at their upper ends with prongs 12 and intermediate their ends with other prongs 13 adapted to be embedded into the material 50 of the heel 14 of a shoe or boot. At its lower face near the end equipped with the spaced fingers 11, the plate 10 carries depending ground engaging prongs 15, one on each side,

and intermediate its ends the plate 10 carries 55 similar depending ground engaging prongs 16, one on each side.

A sliding plate 17 provided with longitudinal slots 18 on each side of its longitudinal central axis is slidably engaging the lower 60 face of plate 10 and the prongs 16 of plate 10 extend through the slots 18 for guiding the plate 17 during its sliding motion. At its free end the sliding plate 17 carries upright prongs 19, adapted to engage the material of the heel and located to both sides of a marginal recess 20 in the end of plate 17. At the inner edge of the recess the plate 17 is equipped with two depending ground 65 engaging prongs 21.

Pintles 22 at the end of a yoke 23 engage 70 pivotally the prongs 16, and the connecting bar at the opposite end of the yoke has an angular arm 24 through which extends a shank 25 carrying at its outer end an operating knob 26 or the like, and at its inner end a locking plate 27 adapted to be passed in one of its positions through the space between fingers 11 and in its turned or locking 75 position engage the inner faces of these fingers in the manner illustrated in Figure 5.

The longitudinal branches of the yoke 23 carry on their inner edges flanges angularly disposed to the said branches and each provided with a plurality of perforations 28 80 adapted to be engaged by the hooked ends of a spring 30 having substantial U-shape. The connecting bar of the U-spring branches are rotatably arranged in a socket 31 attached to the lower face of the slide plate 90 17. Between the branches of the yoke 23, a bar 32 is integrally made with the connecting bar of the branches of the yoke, and its other end is attached to a median bar 33 of the stationary plate 10 which has its 95 material cut out to both sides of this bar 33, as at 34 and 35.

The operation of the device is evident 100 from the above description. If the device is to be attached to a heel, the yoke is turned around the pivot points 22 to assume the position illustrated in Figure 2, while the ends of spring 30 are introduced in the respective holes of the flanges 28 in order to adjust and lock the parts in their respective positions fitting the particular size and heel. When then the yoke is swung about the pivot points 22 and the locking plate is 105

passed through the space between fingers 11, and turned behind the same by means of knob 26 so as to engage the rear faces of the fingers in the manner illustrated in Figure 5, the device will be firmly secured to the heel as the prongs 12, 13 and 19 will be firmly embedded into the material of the heel.

It is to be understood that changes may be made in the general arrangement and in the construction of the minor details of my invention without departing from the scope and spirit of the same as defined in the appended claims.

Having thus described my invention, what I claim as new and desire to protect by Letters Patent is:

1. In a device of the class described, the combination of a stationary and a movable plate, a yoke on said movable plate having the lower ends of its branches attached to the stationary plate, a median bar on said yoke attached at its lower end to said stationary plate, perforated flanges on the branch bars of said yoke angularly disposed thereto, and a U-spring adapted to engage with its hook-shaped free ends into the perforations of said flanges, and a socket on

said movable plate in which the connecting bar of the U-spring is turnably located.

2. In an antislipping device of the class described for the heels of foot wear, the combination of a stationary plate, a median bar on said plate and openings in said plate to both sides of said median bar, with a sliding plate adapted to slide over the lower face of said stationary plate, ground engaging prongs on said stationary plate intermediate the ends thereof, a yoke having pintles at its lower ends pivotally engaging said prongs, a median bar on said yoke having its free end secured to the median bar of said stationary plate, two upstanding spaced fingers at one end of said stationary plate, a locking plate on said yoke adapted to be introduced through the space between said fingers behind the same and to be turned for locking the parts in their adjusted position, and means for allowing an adjustment and locking of the relative positions of both plates for any size of heel.

Signed at New York, in the county of New York and State of New York, this day of November 18 A. D. 1924.

JOHN GEMZA.
